SAMUEL D. RANDOLPH, OF FORT WORTH, TEXAS

POWER-SAVING JACK

Application filed September 13, 1929. Serial No. 392,291.

My invention relates to power saving jacks and more particularly to a jack for conserving the power and which will stand balanced at almost any point in the working beat; and the object is to provide a power jack in which provision is made for shifting the resistance to off-set the load during operation and to convert the resistance from a total loss or dead weight into a working force or energy. 10 One of the advantages of the machine is that the load is carried directly vertically and there is no side thrust of the plunger or sucker rod. Another advantage is that the machine can be operated with a very small 15 amount of power. Other objects and advantages will be fully explained in the following description and the invention will be more particularly pointed out in the claims.

Reference is had to the accompanying 20 drawings which form a part of this application.

Fig. 1 is a side elevation of the power jack.

Fig. 2 is a detail plan view of the crank and the crank connections.

25 Fig. 3 is a perspective view of the same.

Fig. 4 is a plan view of the power jack.

Fig. 5 is an end elevation of the same.

Fig. 6 is a detail view of the bearings for the crank connections.

30 Fig. 7 is a side elevation of a power jack which shows a slight variation from the machine as shown in the previous views.

Fig. 8 is a side elevation of a power saving jack, showing a modification of the jacks 35 previously shown.

Similar characters of reference are used to indicate the same parts throughout the several views.

The jack is provided with three pairs of 40 supporting frame members 1-1, 2-2, and 3-3. All of these upright frame members have supporting bases 4. The machine is also provided with upright bearing members 5-5 for supporting the main crank-shaft 6. 45 The members 5-5 may be forked as shown in Fig. 1. The machine or jack is provided with a walking beam 7 which is provided with a movable fulcrum 8 and a co-operating movable fulcrum 9. The fulcrum 8 is connected 50 to a lever 10 by a link bar 11 and the link

bar 11 is pivotally connected to a controlling brace 12 which causes a vertical or perpendicular movement of the sucker rod 13. The lever 10 is fulcrumed in the uprights 2-2. A link bar 14 is pivotally connected to the lever 10 and to a lever 15 which is mounted on a movable fulcrum 16. A link bar 17 is pivoted on the fulcrum 16 and pivotally connected to a movable beam 18. The beam is fulcrumed on a movable fulcrum 19. 60 A link bar 20 is pivotally connected to the fulcrum 19 and to the co-operating movable fulcrum 9. The fulcrum 9 is carried in a walking beam 21 which is fulcrumed on the uprights 3. A pitman rod 22 is pivotally 65 connected to the walking beam 21 and pivotally connected to crank arms 23 of the crank shaft 6 by a pivot bolt 24. A pitman rod 25 is pivotally connected to the crank arms 26 and pivotally connected to the walking 70 beam 7. Supplemental crank arms 23 are held in fixed parallel relation to the crank arms 26. The arms 23 have grooves 27. The bolt 24 has a cylindrical portion for connection of the pitman rod 22 and flat or 75 square portions 28 on each side of the cylindrical portion and reduced threaded portions 29 which are screwed into the arms 23. Cleats 30 are bolted to the arms 23 on both sides of the flat portions. This makes the 80 pivot bolt 24 non-revolute in the arms 23. The pitman rod 25 is pivotally connected to studs 31 which are integral with arms 23. The studs 31 have flat or square portions 32 which fit in grooves 33 in the arms 26 so that 85 the studs 31 and the arms 26 are non-revolute relative to each other. The object of this construction is to make the parts demountable.

A lever 34 is fulcrumed on a pivot bolt 35 which is mounted in the frame members 3. Link bar 36 is pivotally connected to the lever 34 and to the walking beam 7 and link bar 25. The same pivot bolt 37 serves for all three elements, link bar 25, walking beam 7 90 and link bars 36. A link bar 38 is pivotally connected to the walking beam 15 and to the lever 34 and a link bar 39 is pivotally connected to walking beam 18 and to the lever 34.

In the variation shown in Fig. 7, a link 100

bar 40 is pivotally connected to the walking beam 7 and to a floating auxiliary walking beam 41. A link bar 43 is pivotally connected to the beam 41 and to the beam 42 which is fulcrumed on the frame member 2. The link bar 36 is pivotally connected to the lever 34 and to the beam 42. A walking beam 44 is fulcrumed on the upright 2. A link bar 45 is pivotally connected to the beam 44 and to beam 41. A link bar 46 is pivotally connected to the beam 44 and to the walking beam 21.

In operation, power is applied to drive the shaft 6 and this shaft actuates the arms 26 which drives the link bar 25. This bar 25 actuates the walking beam 7 and the lever 34. The walking beam 7 actuates the pull rod 13. At the same time, the link bar 36 actuates the lever 34 and power is transmitted by the link bars 36 and 39 through the lever 34 and link bar 36 and the power thus transmitted cooperates with the power from the crank shaft to operate the beam 7. The vertical movement of the sucker rod 13 is accomplished by the control bar 12. The power is compounded from the beam 7 through the link bar 11, beam 10, link bar 14, and walking beam 15. The power thus coming through the beam 15 is compounded with the power coming through the link bars 36 and 39 to actuate the walking beam 18 and the compounded power is transmitted through the walking beam 18 and walking beam 21 and thence through the link bar 22 to cooperate with the power of the crank shaft 6. A power pulley 50 is provided for driving the crank shaft 6.

Various changes in the construction, proportion, and arrangement of the several parts may be made without departing from my invention.

To illustrate the effect of the several levers and beams and link bars: If a pound is to be raised by the rod 13, apply a pound of power to the pivot connection 37 plus enough power to break the balance and take care of the friction. This will create a double power and make two pounds bear on the pivot connection 8, minus the friction. This two pounds will be transmitted through the link 11 to the beam 10. The same two pounds will be transmitted upwardly through the link 14 which draws the beam 15 upwardly. The same two pounds will pull upwardly on the beam 15. Enough power to equal this two pounds will have to be applied through the beam 34 and bracket 34' and link bar 38. This will make an upward pull on the pivot 16 and beam 15 of four pounds. This will pull upwardly on the four pounds on one end of the beam 18. Then sufficient power must be created in beam 34 and transmitted through bracket 34' and link bar 39 to the other end of beam 18 to equalize the four pounds upward pull by link 17 on beam 18 thereby giving an eight pound pull on pivot 19 and beam 18. The same eight

pounds will be drawn upwardly through link 20 to pivot 9 of beam 21. Beam 21 is ratioed two to one and this will give a downward pull of four pounds on the other end of beam 21 which is attached to pitman 22. Pitman 22 is pivotally connected to crank pin 24. The crank is driven by the shaft 6 and a power pulley 50. This downward pull on link 22 will equal the upward pull on link 25 thus creating a balance. The upward pull on link 25 will be only one-half of the downward pull on link 22 because of the longer crank which is necessary to give the movement or stroke on the power end of beam 7.

The operations give a rectilineal motion to the beam 7 by reason of the pivotal connection of the link bar 12 to the bracket 12' which is stationary on the post 1. A vertical rectilineal motion is given to the sucker rod 13 because the pivot *a* always moves in the same vertical line, there being no arc in the movement of the pivot *a* because the arc is made by the pivot 8.

The mechanical advantage gained is due to the fact that the work is done through a lesser distance than that through which the power moves. This is accomplished by providing a floating fulcrum 8 for the walking beam and providing a system of levers for coordinately operating this fulcrum for moving the fulcrum in a direction to shorten the movement of the power end of said walking beam during the movement of the walking beam on said fulcrum. Such operations result from the shorter stroke of the power end of the walking beam than is transmitted by the throw of the crank arm on the power shaft 6.

In the form of the power jack shown in Fig. 8, there is a modification of the power jack as shown in Fig. 1 and in Fig. 7. An additional link bar 51 is pivotally connected to beam or lever 34. The pivot 8, link bar 40, beam 44, link bar 41, link bars 43 and 46, beam 42, all operate in the same manner as above described. The link bar 51 is pivotally connected to a beam 52 and pulls upwardly on this beam. A link beam 52 pushes downwardly on a beam 54. The beam 52 is fulcrumed on posts 2. The link bar 22 is pivotally connected to beam 54 and the beam 54 has a slot 55 for the movement of crank 26. The link bar 25 is pivotally connected to the crank 26, as in previous views, and the link bar 25 acts on the beam 7 and on link bar 36 which operates beam 34. The link bar 46 and the beam 21 operate in the manner before described. The beam 54 is fulcrumed on the crank 26.

What I claim, is:—

1. A power saving jack comprising an upright frame consisting of a work end frame, a power end frame, a bearing frame, and a fulcrum frame, a walking beam operatively connected to said work end frame member

and operatively connected with said power end frame member, and link bars and levers pivotally connecting the ends of said walking beam to said fulcrum frame member, and means operatively connected with said bearing frame for driving said walking beam.

5. A power saving jack comprising an upright frame consisting of a work end frame member, a power end frame member, a bearing frame, and a fulcrum frame member, a walking beam, a lever and a pair of link bars pivotally connecting said walking beam to said work end frame member, a pair of levers and a pair of link bars pivotally connecting the power end of said walking beam to said first named lever, and means operatively connected with said bearing frame for driving said walking beam.

6. A power saving jack comprising an upright frame consisting of a work end frame member, a power end frame member, a bearing frame, and a fulcrum frame member, a walking beam, a lever fulcrumed on the said fulcrum frame member, link bars operatively connecting said lever and the work end of said walking beam, a power transmitting lever fulcrumed on said power end frame member and operatively connected to said walking beam, a pair of link bars and a lever operatively connecting said power transmitting lever to said first named lever, and means operatively connected with said bearing frame for driving said walking beam.

7. A power saving jack comprising an upright frame consisting of a work end frame member, a power end frame member, a bearing frame, and a fulcrum frame member, a walking beam, a lever fulcrumed on said fulcrum frame member, link bars operatively connecting said lever to the power end of said walking beam, a driving wheel and a crank therefor journaled in said bearing frame, a power transmitting lever fulcrumed on said power end frame member and operatively connected to said crank, and a lever and a pair of link bars operatively connecting said power transmitting lever to said first named lever.

8. A power saving jack comprising an upright frame consisting of a work end frame member, a power end frame member, a bearing frame, and a fulcrum frame member, a walking beam, a lever fulcrumed on said fulcrum frame member and link bars operatively connecting said lever and walking beam, a driving wheel and a crank therefor journaled in said bearing frame, a power transmitting lever fulcrumed on said power end frame member and link bars pivotally connecting said power transmitting shaft and said walking beam and said crank, a pair of link bars, a lever and a link bar operatively connecting one of said link bars to said first named lever and a link bar and a lever operatively connecting the other link bar to

the last named link bar, a balancing lever fulcrumed on said power end frame member, a link bar operatively connecting one end of said balancing lever to the last named lever, and a link bar operatively connecting the other end of said balancing lever to said crank.

In testimony whereof, I set my hand, this 20th day of June, 1928.

SAMUEL D. RANDOLPH.
